Primary Examiner — Eric Goodman*Assistant Examiner* — Sloan Rozin(74) *Attorney, Agent, or Firm* — Cantor Colburn LLP(57) **CLAIM**

We claim, the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof; and,

FIG. 4 is the fourth image thereof.

The broken lines showing portions of the display screen or portion thereof with animated graphical user interface are for the purpose of illustrating environment and forms no part of the claimed design. The broken line showing of elements on the display screen illustrate portions of the article and form no part of the claimed design.
